UNITED STATES PATENT OFFICE.

NATHANIEL BANKS CREGIER, OF CHICAGO, ILLINOIS.

RECTIFYING DEVICE.

Application filed May 25, 1925. Serial No. 32,651.

This invention relates to rectifying devices in general and more particularly to such devices as are adapted for use as detectors for radio sets.

5 It is an object of this invention to provide a rectifying device in which crystals such as silicon or any suitable granular or solid rectifying material, are used and which is provided with a multiplicity of contact 10 points which are adapted to be simultaneously and readily actuated to contacting position with said crystals to insure the obtaining of a satisfactory contact therewith in a prompt and efficient manner.

15 It is further an object of this invention to provide a rectifying device in which the crystals are flexibly supported.

It is also an object of this invention to provide a rectifying device which is simple, 20 rugged and economical of manufacture.

It is also an important object of this invention to provide a rectifying device which may easily and simply be operated.

Other and further important objects of 25 this invention will be apparent from the disclosures in the specification and the accompanying drawings.

This invention (in a preferred form) is illustrated in the drawings and hereinafter 30 more fully described.

On the drawings:

Figure 1 is an elevational view of a device embodying this invention.

Figure 2 is an elevational view of the device partly in section.

Figure 3 is a detail bottom plan view with parts removed, of the upper contact member.

Figure 4 is a detail plan view with parts removed, of the bottom contact member.

As shown on the drawings:

Referring to Figure 1 there is shown a plate 1 which may be of conducting material. Supported on the plate 1 is an arm 2 which is secured on said plate by nuts 3. The nuts 3 are adapted to be used to connect an electrical lead (not shown) to an upper contact screw 4 threaded in the arm 2. The screw 4 has provided thereon a square head 5 which is apertured on all four sides to receive a small arm or handle 6 for a purpose which will be hereinafter apparent. Threaded on the screw 4 is a collar 7 which is provided with a setscrew 8.

55 Mounted on the plate 1 below the arm 2 is a supporting member 9 which is insulated

from the plate 1 by insulating members 10. The member 9 is secured to the plate 1 by nuts 9^a. Supported in the member 9 is a cup member 11 which is open at either end and is counterbored from the upper end to provide a shoulder 12 on which rests a metallic diaphragm 13. Above the diaphragm 13 is a flexible screen or corrugated member 14. Above the member 14 within the cup 11 is a hollow insulating member 15. Within the member 15 on the screen 14 is a plurality of crystal particles 16. Supported by means of an annular member 17 on the member 15 is a plunger 18 which is secured to a pin 19 slidable in the member 17. Surrounding the pin 19 is a compression spring 20 which is adapted to engage between a dowel pin 21 in the pin 19 and the upper side of the annular member 17. Suitably secured to the bottom surface of the plunger 18 is a screen or corrugated member 22 (Figures 2 and 3). The upper end of the pin 19 is adapted to be engaged by the lower extremity of the screw 4 for forcing said pin downwardly against the action of the spring 20 to cause the screen 22 to contact the crystal particles 16. Surrounding the member 17 and insulated therefrom by a disk 23 is an apertured cap member 24 which 85 threadedly engages the cup 11. The nuts 3 and 9^a respectively form the means for connecting the device in the circuit.

In operating the device, the screw 4 which is preferably provided with threads of relatively small pitch, is turned by means of the arm 6 until the screen 22 contacts the crystals 16 as desired. The collar 7 is then secured in position on the screw 4 to limit further turning of the screw 4 to prevent 95 packing the crystals 16 on any subsequent minor adjustment of said screw. The arm 6 is then positioned in the proper aperture in the head 5 so as to limit the unscrewing of the screw 4 to less than one revolution of 100 said screw, the length of said arm being such that it will strike the plate 1 if a complete revolution of said screw is attempted.

The screens 22 and 14 being adapted to engage the crystals 16 at a multiplicity of points practically at the same time, a satisfactory "hot spot" is assured by merely turning the arm 6 about the pivot 4 less than one revolution. The provision of the flexible diaphragm 13 permitting vibration of 110 the crystals 16 enables the operator of a radio set to obtain a clearer tone than if

said crystals were rigidly supported in the cup 11.

I am aware that many changes may be made and numerous details of construction 5 may be varied through a wide range without departing from the principles of this invention, and I therefore do not purpose limiting the patent granted hereon, otherwise than necessitated by the prior art.

10 I claim as my invention:

1. A device of the class described comprising a receptacle adapted to support a detecting substance and a contact member adapted to be actuated to contact with said 15 substance, a spring surrounding said member for holding the same in retracted position, and screw means adjustably supported above said member for engaging the same to contact position and means to prevent a complete revolution of said screw means.

2. A device of the class described comprising a receptacle adapted to support a detecting substance, a contact member adapted to be actuated to contact with said

substance, a spring surrounding said member for holding the same in retracted position, screw means adjustably supported above said member for engaging the same to contact position, means to prevent a complete revolution of said screw means and a 30 limiting collar adjustably mounted on said screw member above its support.

3. A device of the class described comprising a receptacle adapted to support a detecting substance, a contact member 35 adapted to be actuated to contact with said substance, a spring surrounding said member for holding the same in retracted position, screw means adjustably supported above said member for engaging the same to 40 contact position, and a detachable arm adapted to be adjustably secured on said screw to prevent a complete revolution of said screw substantially as described.

In testimony whereof I have hereunto 45 subscribed my name.

NATHANIEL BANKS CREGIER.
